UNITED STATES PATENT OFFICE.

HARRY STERENBUCH AND SAM STERENBUCH, OF NEW YORK, N. Y.

DESIGN FOR A PAPER BAG.

57,023.

Specification for Design.

Patented Jan. 25, 1921.

Application filed November 11, 1919. Serial No. 337,269. Term of patent 7 years.

To all whom it may concern:

Be it known that we, HARRY STERENBUCH, subject of Russia, and SAM STERENBUCH, citizen of the United States, and residents of New York city, in the county of New York and State of New York, have invented a new, original, and ornamental Design for a Paper Bag, of which the following is a specification, reference being had to the accompanying drawing, forming part thereof.

The figure is a perspective view of a paper bag, showing our new design.

We claim:

The ornamental design for a paper bag as shown.

Signed at New York city, in the county of New York, and State of New York, this eighth day of November, A. D. 1919.

HARRY STERENBUCH.
SAM STERENBUCH.
